HAIR CURLER

William H. Maxwell, Beverly Hills, Calif.

Application January 10, 1944, Serial No. 517,652

10 Claims. (Cl. 132—41)

This invention relates to hair curlers and has particular reference to hair curling devices of the type wherein a strand of hair is wound on a spindle to remain in the wound or curled state for a substantial period or until it acquires the desired curled contour. A general object of this invention is to provide a practical, effective and very inexpensive hair curler of the character mentioned.

This application is filed as a continuation in part of my pending application entitled "Hair curler," Serial No. 400,945, filed July 3, 1941.

An object of this invention is to provide a hair curler of the character referred to that is economical to manufacture and extremely inexpensive, being so low in cost that it may be discarded after use. The curler of the present invention is so inexpensive that it may be discarded following a single use. This feature of the invention particularly adapts the curler for use in beauty salons and other commercial establishments where it is very desirable to maintain the highest degree of cleanliness and where it is important to employ single use articles and equipment whenever possible. The advantage of the single use also recommends the curlers to others. In all cases, whether commercial or otherwise, the employment of the curlers of the invention eliminates the necessity of maintaining a supply of permanent metal curlers and of washing such curlers after use. It is to be understood that the curler of the present invention may be made of permanent and lasting materials in which case it is not necessarily discarded after use but may be retained for repeated use.

Another object of the invention is to provide a hair curler of the character referred to that is formed to not only curl the hair but to also impart a wave to the strand being curled.

Another and important object of the invention is to provide a curler of the character mentioned that can be worn or left on the hair for an indefinite period without discomfort and without danger of injury to the scalp. The curlers of the present invention may be formed of a pliant material which cannot scratch, cut or bruise the skin or scalp and the curler may, if desired, be worn while sleeping without discomfort or injuring or endangering the user.

Another object of this invention is to provide a hair curler of the character mentioned that may be inexpensively formed from a single integral piece of paper, fiberboard, cardboard or other foldable flexible material.

Another object of this invention is to provide

a hair curler of the character referred to that may be marketed and delivered in a flat condition to be stored and handled with the utmost of convenience or, if desired, may be delivered and stored in the folded condition to be ready for immediate use.

Another object of the invention is to provide a curler of the character mentioned that has spindle arms which cooperate to form a hair receiving spindle that is substantially round in cross sectional configuration.

The various objects and features of my invention will be fully understood from the following detailed description of typical preferred forms and 15 applications of my invention, throughout which description reference is made to the accompanying drawings, in which:

Fig. 1 is a plan view of a curler of the present invention in the extended or flat condition. Fig. 20 2 is a view similar to Fig. 1 with one spindle arm folded to the operative position. Fig. 3 is a view similar to Fig. 1 illustrating both spindle arms in the folded-over operative position. Fig. 4 is a perspective view of the curler illustrating the 25 manner in which the end of a hair strand may be started or introduced into the spindle for wrapping thereon. Fig. 5 is an edge or side elevation illustrating the hair strand wrapped on the spindle with the spindle latched or retained in the 30 operative position. Fig. 6 is a view similar to Fig. 1 of another form of the invention. Fig. 7 is a sectional view taken on line 7—7 of Fig. 6. Fig. 8 is a sectional view taken on line 8—8 of Fig. 6. Fig. 9 is a side view of the curler formed from 35 the blank shown in Fig. 6, showing the tubular spindle formation and Fig. 10 is a section taken on line 10—10 of Fig. 9.

The improved curler of the present invention 40 may be said to comprise, generally, a body 10 and spindle means 11 on the body on which the hair is to be wound.

The curler of the invention is preferably, though not necessarily, formed of a foldable flexible and pliant material such as paper, cardboard, 45 fiberboard, and the like, and in the preferred construction the entire curler is constructed of a single piece or blank of such material. The formation and character of the curler are such that the device may be formed of other materials 50 having the desirable properties of flexibility, etc. and it will be apparent that the curler may be constructed of two or more pieces or members, if desired, and the present invention is not to be construed as limited to the particular preferred 55 embodiment illustrated in the drawings comprised

of a single body or blank. For general use it is desirable to form the curler of a waterproof or non-absorbent material. For special purposes, however, it may be formed of absorbent material or may be impregnated or coated with hair treating preparations which will act on the hair while the hair is on the curler. Such preparations may be in the nature of hair tonics or may be preparations operating to aid in the curling or setting of the hair. As an example, if the curler is formed of paper it may be treated with a suitably refined petroleum oil such as will give dry hair a suitable amount of oiliness and luster.

The body 10 carries the spindle means 11 and serves as a keeper for latching or holding the spindle means in its operative condition. The body 10 is an elongate element preferably reduced, at what I will term, its inner end to have a tongue 12. The tongue 12 carries the spindle means and is separated therefrom by fold lines 13, as will be more fully described. The longitudinal edges 14 of the body 10 may be straight and generally parallel as illustrated and the outer end of the body is preferably rounded. It will be obvious, however, that the longitudinal edges of the several parts, the body as well as the spindle, may be shaped in any desired manner to give the hair applied thereto the desired configuration. It may be preferred to provide a series of longitudinally spaced openings 15 in the body 10 to facilitate drying of the hair and to provide ventilation.

The spindle means 11 constitutes a mandrel or shaft on which the hair is to be wound. The spindle means 11 is preferably a split, divided or compound structure adapted to retain the end portion of the strand S of hair which is to be curled. In the preferred construction, the spindle means 11 includes two tines, fingers or arms 16 and 17, it being understood that the invention contemplates the use or provision of but a single spindle arm, if desired. The two spindle arms 16 and 17 are preferably alike and complementary and are elongate parts of substantially the same length as the body 10. The arms 16 and 17 may be considerably narrower than the body 10. In the form illustrated the arms have straight generally parallel edges and are rounded at their outer ends.

When the curler is formed of one piece, as illustrated, the arms 16 and 17 are integrally joined with the tongue 12 of the body 10. In the particular form illustrated the arms 16 and 17 are joined with the sides of the tongue 12 along the fold lines 13, these lines or the material at these lines forming the hinge connections between the spindle arms and the body 10. The hinge lines or fold lines 13 extend parallel with the longitudinal axis of the curler and are preferably set in from the longitudinal edges 14 of the body 10 so that the tongue 12 is narrower than the body 10, as above described. Pitched or angular cuts 18 extend inwardly and rearwardly from the body edges 14 to the hinge lines or fold lines 13. It may be preferred to prepare the material for folding along the lines 13 by providing lines of scoring, this being particularly true when the curlers are to be marketed and delivered in the flat condition. The spindle arms 16 and 17 are adapted to be individually and bodily folded or hinged inwardly along their respective fold lines 13 to lie in generally parallel relation to a face of the body 10. Thus, as shown in Fig. 2 of the drawings, the spindle arm 16 is folded or swung inwardly to lie against the face

of the body 10. Following this inward folding of the arm 16, the spindle arm 17 is hinged or folded along its line 13 to overlie the previously positioned arm 16. Fig. 3 of the drawings illustrates the manner in which the arms 16 and 17 are folded one against the other to lie generally parallel with a side or face of the body 10. These folding operations, that is, the inward folding or swinging of the arms 16 and 17 may be performed at the time of manufacture of the curler or may be performed manually when the curler is to be put into use. The curler may be used when the parts are merely folded into position, as just described, or a suitable fastening means or adhesive may be applied to the several overlying or adjoining parts or surfaces at or opposite the tongue 12 so that the curler is fixed in the folded condition ready for use.

The two spindle arms 16 and 17 are adapted to be swung outwardly or laterally as a unit to receive and hold the end portions of the hair strand S so that the strand may be wound on them and are then swung inwardly and latched with the body 10 so that the hair is held in the rolled or wound condition. The arms 16 and 17 are adapted to be hinged or swung outwardly along transverse lines 19 adjacent the tongue 12. As shown, the lines 19 extend outwardly or laterally from the points of joinder of the body edges 14 with the cuts 18. The lines 19 of folding or hinging may or may not be formed during the manufacture of the curler. In some cases it may be desired to score the arms 16 and 17 along the lines 19 to facilitate the hinging or swinging of the arms while in other cases these portions of the device may be left plain to bend along or in the vicinity of the lines when the device is put into use.

The outer or free ends of the spindle arms 16 and 17 are adapted to be retained or latched in the outer end part of the body 10, when the hair strand S has been wound on them, to retain the hair in the spooled or wound condition. The means for retaining or latching the spindle arms 16 and 17 to the outer portion of the body 10 comprises an opening or transversely elongated slot 20 in the outer portion of the body. The slot 20 is of sufficient length and width to receive the end portions of the two spindle arms 16 and 17 when the arms are laid one against the other and is preferably made sufficiently large so that the arms can be readily inserted. The spindle arms 16 and 17 carrying the wound hair strand S are bent forwardly and inwardly and are entered in the opening 20. The resiliency of the arms 16 and 17 and of the body 10 holds the arms latched or locked in the opening 20. As illustrated in Fig. 5 of the drawings the rolled up hair strand S bows or flexes both the body 10 and the two arms 16 and 17 outwardly between their ends and the bowing or flexing of these parts holds the arms 16 and 17 securely in the opening 20. The body 10 latched with the arms 16 and 17 and bearing against the wound hair strand S dependably prevents unwinding of the hair. Each of the arms 16 and 17 may, if desired, be provided on one edge with notches 30 and the folding of the arms on the lines 13 may be such that the arms bear edgewise, preferably in opposite directions, in the slot 20 to grip the wall of the slot and further resist displacement of the arms from the slot.

It is believed that the utility and practicability of the hair curling device of this invention will be readily understood from the foregoing detailed

description. The curler may be marketed either in the condition shown in Fig. 1 of the drawings or in the folded together condition illustrated in Fig. 3. If the curler is supplied in the flat state as shown in Fig. 1 of the drawings it is readily prepared for use by merely bending the arms 16 and 17 inwardly along the lines 13 to rest one against the other at the face of the body 10. The arms 16 and 17 are swung outwardly from the body 10 along the lines 19 and the end of the hair strand S is introduced between the arms as illustrated in Fig. 4. The strand S or a selected portion of the strand S is then wound around the two arms 16 and 17 to provide a spool or body of hair as shown in Fig. 5. The free or outer ends of the arms 16 and 17 are then bent inwardly and passed through the opening 20. The latching or retention of the spindle arms 16 and 17 with the outer portion of the body 10 results in longitudinal bowing of the body 10 as well as bowing of the spindle arms. This is clearly shown in Fig. 5 of the drawings. The body 10 latched with the arms 16 and 17, as just described, effectively prevents the hair strand S from unwinding and retains the curler in position on the hair.

The curler may be left on the hair for a selected prolonged period to give the hair a good curl or set. If desired, the curler may be left on the hair while the user sleeps. The hair strand S wound on the spindle arms 16 and 17 takes or assumes a curled contour. Further, the strand being wound around the sharp edged flat sided arms 16 and 17 is given a wave comprised of spaced undulations where the hair passes around the edges of the spindle arms. Accordingly, the device not only curls the hair but also waves it. When it is desired to remove the curler the spindle arms 16 and 17 are merely withdrawn from the opening 20 and the spindle arms are slid from the hair. Where the curler is formed of paper, or the like, and is used in beauty parlors, etc., it may be discarded following use. On the other hand, where the curler is formed of more permanent material it may be retained for repeated re-use.

In Figs. 6 to 10 of the drawings I show a modified form of construction characterized by the fact that the arms 16^a and 17^a instead of being flat, as shown in the form of the invention above described, are curved so that the hair carrying portion of the spindle formed by them is substantially round in cross-section. This form of the invention is further characterized by the fact that the body 10, instead of having openings 15 and 20, has a single longitudinal opening 20^a, the outer end portion of which serves the function of the opening 20 above described, while the balance thereof serves the function of the openings 15 and, further, gives desirable flexibility to the body to aid in its cooperation with the spindle formed by the arms 16^a and 17^a. The device of Figs. 6 to 10 may be similar, generally, to that above described, as will be noted from a comparison of Figs. 1 and 6.

To avoid kinking the hair it is desirable in some cases that the spindle be round or substantially round in cross-section. At the same time it is desirable that the spindle formed by the arms 16^a and 17^a have a certain degree of flexibility. The flexibility is desired at the end portions of the arms. In the preferred form of the invention I cup or curve the middle portions A of the arms so that they are substantially semi-circular in cross section. I leave the inner end

portions B of the arms flat and I also leave the outer portions C of the arms flat.

The curved portions A are oppositely cupped, as shown in Fig. 6, so that the arms can be overlapped causing the curve of one arm to be downward and the curve of the other arm to be upward, with the result that the spindle formed by the arms is substantially round in cross-section, as shown in Fig. 10. It is to be understood, of course, that the curvature does not have to be such as to make the spindle fully round, but only needs to be enough to take away the corners or sharpness that would otherwise cause kinking or sharp bends in the hair. The portions A, being cup-shaped or curved in cross-section, have desirable rigidity at the portion where the hair is wound, while the portions B afford desirable flexibility in the region where the arms are hinged to the body. The portions C, being flat, are flexible, allowing them to be inserted into the opening 20^a to join the outer end of the spindle with the body. In other particulars or details the form of the invention shown in Fig. 6 may be the same as that hereinabove described.

Having described only typical preferred forms and applications of my invention, I do not wish to be limited or restricted to the specific details herein set forth, but wish to reserve to myself any variations or modifications that may appear to those skilled in the art or fall within the scope of the following claims:

Having described my invention, I claim:

1. A hair curler comprising an elongate body, an elongate spindle arm hinged adjacent one end of the body to swing about an axis extending longitudinally of the body, and means for latching the free end of the arm with the other end portion of the body.

2. A hair curler comprising an elongate body, elongate flexible spindle arms hinged to one end portion of the body to swing about spaced axes extending longitudinally of the body so that the arms may be folded one over the other at a face of the body, and means for releasably engaging the free ends of the arms with the other end portion of the body.

3. A one-piece hair curler comprising a one-piece sheet member including an elongate body, arms integrally hinged to one end portion of the body along lines of bending which extend longitudinally of the body so that the arms may be swung one against the other at a side of the body, and means for releasably latching the free ends of the arms with the other end portion of the body when hair is wound on the arms comprising an opening in said end portion of the body into which the arms are entered.

4. A one-piece hair curler comprising a one-piece sheet member including an elongate body, arms hinged to one end portion of the body along lines of bending which extend longitudinally of the body so that the arms may be swung one against the other at the side of the body, transverse lines of bending in the arms adjacent the first mentioned lines so that the arms may be swung laterally from the body to receive the hair, and means for releasably latching the free ends of the arms with the other end portion of the body when hair is wound on the arms comprising an opening in said end portion of the body into which the arms are entered.

5. A hair curler comprising a one-piece sheet member including an elongate body, and spindle arms integrally hinged to one end portion of the body to swing about spaced axes extending longi-

tudinally of the body so that the arms may be folded one over the other at a face of the body, means for securing the arms together at said end portion of the body to hold the arms in the positions where they are folded one over the other, and means for releasably latching the free ends of the arms with the other end portion of the body.

6. A hair curler comprising a one-piece sheet member including an elongate body, the body having an opening adjacent one end, and spindle arms integrally joined with the opposite edges of the other end portion of the body and adapted to be folded one over the other at a face of the body, and means for holding the arms where they are folded one over the other at said other end of the body, the outer ends of the arms being adapted to be entered in said opening to be releasably retained therein.

7. A hair curler formed of sheet material comprising an elongate body, an elongate spindle arm hinged adjacent one end of the body on an axis extending longitudinally of the body to overlie the body, the arm being curved in cross-sectional configuration.

8. A hair curler formed of sheet material including an elongate body, and a pair of arms

hinged adjacent one end of the body on axes extending longitudinally of the body to be adjacent each other and to overlie the body, the arms being oppositely curved in cross-section to form a substantially round hair receiving spindle.

5 9. A hair curler comprising an elongate body, an elongate spindle arm hinged adjacent one end of the body to swing about an axis extending longitudinally of the body, and means for latching the free end of the arm with the other end portion of the body, including an elongate opening in the body to receive a part of the arm.

10 10. A hair curler comprising a one-piece sheet member including an elongate body, and spindle arms integrally hinged to one end portion of the body to swing about spaced axes extending longitudinally of the body so that the arms may be folded one over the other at a face of the body, the middle portions of the arms being curved in 15 cross-section so the arms together form a substantially round hair receiving spindle, means for securing the arms together at said end portion of the body to hold the arms in the positions where they are folded one over the other, and means for releasably latching the free ends of 20 the arms with the other end portion of the body.

25 WILLIAM H. MAXWELL.
